UNITED STATES PATENT OFFICE.

GEORGE F. CONNER AND JOSEPH WILBUR DOVE, OF PORT HURON, MICHIGAN.

CHAIR.

1,361,446.

Specification of Letters Patent.

Patented Dec. 7, 1920.

Application filed June 5, 1919. Serial No. 302,037.

To all whom it may concern:

Be it known that we, GEORGE F. CONNER and JOSEPH WILBUR Dove, citizens of the United States, and residing at Port Huron, county of St. Clair, and State of Michigan, have invented a new and Improved Chair, of which the following is a specification.

This invention relates to adjustable reclining chairs especially adapted for use by physicians, dentists and barbers, and its object is to provide a chair which may be raised by means of mechanical means and in which the back may be positioned by similar means; which chair may have its seat in sections so that one section may be swung up and back above the other section; which will have a readily adjustable foot rest, and to which may be pivotally attached an arm bearing a cabinet and a seat for the operator. It is essential that the controlling mechanism for the chair adjusting means shall be so positioned and the auxiliary seat be so mounted that the operator can manipulate the controlling mechanism without leaving his seat. By having the controlling mechanism convenient to the operator it becomes unnecessary for him to leave his seat when he wishes to adjust the chair.

This invention consists in a chair adapted to be lifted and to have the position of its back controlled by mechanical means, in combination with controlling devices for said mechanical means whereby the action of said means may be limited. It more specifically consists in a chair mounted on a rotatable plunger slidable in a vertical cylinder and adapted to be lifted by liquid admitted by a foot controlled valve from any source of liquid under pressure, a tiltable back for the chair, a second cylinder mounted under the seat of the chair and a piston therein to position the back, the liquid for actuating the piston passing up through the plunger that raises the chair. It also consists in forming the seat in sections, one of which is movable relative to the other so that it may be swung up to serve as a seat for a child. It also consists in pivoting an upwardly curved arm on the base supporting the chair and in mounting a small seat on said arm so that the operator may make use thereof at any desired point. It also consists in adjustably mounting an electric light on said arm. It also consists in mounting a basin on said arm and in constructing the arm to carry the supply and waste pipes

for said basin, said basin being adjustable on the arm. It also consists in the details of construction particularly pointed out in the claims.

In the accompanying drawings, Figure 1 is a side elevation of this improved chair, cabinet and seat. Fig. 2 is an elevation of the cabinet with part of its front broken away to show the interior construction. Fig. 3 is a central vertical section of the base of the chair and of the hydraulic cylinders. Fig. 4 is a section on the line 4—4 of Fig. 3. Fig. 5 is a section on the line 5—5 of Fig. 4. Fig. 6 is an inside elevation of a portion of the chair frame. Fig. 7 is a side elevation of the chair with a portion of the seat swung up. Figs. 8, 9 and 10 are sections on the lines 8—8, 9—9 and 10—10 of Fig. 1, respectively. Fig. 11 is a section on the line 11—11 of Fig. 3.

Similar reference characters refer to like parts throughout the several views.

The base 1 of this chair is preferably integral with the cylinder 2 in which the piston 3 is vertically movable. The side frames of the seat are rigidly connected to this plunger and move up and down with it. The diameter of the cylinder is large so that a comparatively light water pressure is sufficient to raise the plunger and chair, and we prefer to use a valve such as shown in Fig. 5 to control the flow of water from the usual city mains through the pipes 5 and 6 to the bottom of this cylinder. The valve body 7 also receives the upper end of a waste pipe 8 and has a three-way plug 9 to connect the pipe 6 to either the supply pipe 5 or waste pipe 8. At the rear end of this plug is an arm 10 to which a tube 12 is connected and within which tube is slidable a rod 13 connected to the collar 14 on the piston 3. The upper end of the tube 12 is nearly closed so that when the button 15 at the lower end of this rod reaches the upper end of this tube, the tube will be moved up with this rod and turn the plug 9 to cut off the flow from the pipe 5. This prevents the plunger being pushed entirely out of the cylinder. At the front end of this plug 9 is a double lever 16 which may be swung by the feet of the operator to turn the plug. The chair may therefore be swung around at will and be caused to rise or lower at will.

The sides 4 of the frame of the chair may connect to a cross head 19 at the top of the piston 3. Each side has secured to it the

guides 21, preferably of metal in which the back 22 is supported through the medium of pins 23 and rollers 24 thereon which are movable in these guides. A cross bar 25 at 5 the bottom of the back (Fig. 3) is shown provided with lugs 26 which receive the pin 27 which extends through one end of the connecting rod 28.

Mounted at the upper end of the piston 10 3 between the sides 4 is a second cylinder 30 having a piston 31 which carries a pin 32 on which the connecting rod is mounted. A passage 33 in the wall of this cylinder connects to the interior of the piston 3 which is 15 slidable on the tube 34. A stuffing box 35 prevents leakage around this tube 34 which connects into the base 1 to register with the passage 36 (Fig. 4). A pipe 37 also connects to this passage and a valve 38 operated by a double foot lever 39 controls the flow of water into and out of the cylinder 30. The feed and waste pipes which 20 connect to this valve and the plug therein may be similar to those shown in Fig. 5. When water is admitted to the cylinder 30, 25 the piston 31 will slide the back 22 to upright position, but when the water is permitted to flow away, the back will slide down to almost horizontal position as indicated by dotted lines in Fig. 1.

Slidable between the side frames 4 of the chair is a seat base comprising a bottom 41, sides 42 having ribs 43 to fit into the guides 21, and upwardly extending brackets 44. 30 A seat is carried by this frame and preferably consists of two parts 45 and 46, the latter being connected to the sides 42 by means of links 47 which permit the seat 46 to be swung up to the position shown in Fig. 40 7 where it may be used by a child whose feet rest on the bottom 41.

The brackets 44 carry pins 48 which pass through the slots 49 in the foot-rest supports 50. The chair arms 52 connect to the 45 pins 53 on the sides and to pins 54 at the upper ends of the supports 50. When the parts are in normal position the supports 50 will be almost vertical, but when the seat base is slid forward as shown in dotted lines in Fig. 1, the foot-rest 56 at the outer ends of the supports 50 will be elevated to about the height of the seat cushions.

The drawings show a tubular arm 60 connected to and supporting a cabinet 61 and 50 having lugs 62 to pivotally receive the arm 63 which carries the seat 64. This arm is hollow and has an enlarged end 65 formed with pins to pivot this end on the base 1 and in the bracket 66 attached to the cylinder 2. Extending up through the base 1 and through a slot in the base 67 of the enlarged end 65 of the arm 60 are three risers 68^a, 69^a and 70^a, connecting to the pipes 68, 69 and 70 respectively by means of knuckles 68^b, 69^b and 70^b which are all on the same

vertical central line with the trunnions of the enlarged end 65. These pipes convey hot and cold water to the basin 72 and carry off the waste water. The bracket 73 for the basin is preferably also the upper 70 end of the waste pipe.

An electric light cable 74 may extend into this enlarged end 65 of the arm 60 and to the lamp 75 on the bracket 76 on the cabinet. The operator may therefore sit on his auxiliary seat 64 which he may swing at will and have at hand his instruments and supplies including the basin of water and have his work illuminated by the lamp 75. He may also swing his seat and his instruments to any desired position and thus save himself as much as possible. He may cause the chair to rise and lower by simply operating the valve and he can also control the back by operating the other valve.

The proportions and details of this chair and its accessories may all be changed by those skilled in the art without departing from the spirit of our invention as set forth in the following claims.

We claim:

1. In a chair, the combination of a base and a chair pivotally mounted thereon and comprising a seat frame and a back, means to cause the chair to rise or lower at will, 95 and means to cause the back to move to upright position and to permit it to move to reclining position.

2. In a chair, the combination of a base and a vertical cylinder thereon, a piston mounted in the cylinder and means to control the height of the piston in the cylinder, a chair frame connected to the upper end of the piston and comprising parallel sides having guides in their opposing faces, a seat slidably mounted in said guides, a back 100 slidably supported by said guides, so it may move from upright to reclining position, and means to move the back to upright position, said cylinder and piston embodying means to control the said means to move said back.

3. In a chair, the combination of a base and a vertical cylinder thereon, a piston mounted in the cylinder and means to control the height of the piston in the cylinder, a chair frame connected to the upper end of the piston and comprising parallel sides having guides in their opposing faces, a seat slidably mounted in said guides, a back 115 slidably supported by said guides, so it may move from upright to reclining position, and means to move the back to upright position, said means comprising a hydraulic cylinder and a piston connected to said 120 back, said vertical piston and cylinder constituting passages for the liquid for the second piston and cylinder.

4. In a chair, the combination of a base and a vertical cylinder thereon, a piston 130

mounted in the cylinder and means to control the height of the piston in the cylinder, a chair frame connected to the upper end of the piston and comprising parallel sides having guides in their opposing faces, a seat slidably mounted in said guides, a back slidably supported by said guides, so it may move from upright to reclining position, and means to move the back to upright position, said means comprising a hydraulic cylinder and a piston connected to said back, said first named piston and the wall of the second named cylinder being formed with passages for the liquid that actuates the piston connected to said back.

5. In a chair, the combination of a base and a vertical cylinder thereon, a hollow piston mounted in said cylinder and means to control the height of the cylinder in the piston, a horizontal cylinder mounted on the piston, a chair frame mounted on the piston to inclose the horizontal cylinder and comprising sides provided with guides in their opposed faces, a seat back slidably supported in said guides, a piston slidable in said horizontal cylinder, means connecting the horizontal piston to the seat back, and means to control the flow of water to the horizontal cylinder, said vertical piston and cylinder constituting passages for the liquid for the second piston and cylinder.

6. In a chair, the combination of a base and a vertical cylinder thereon, a hollow piston mounted in said cylinder and means to control the height of the cylinder in the piston, a horizontal cylinder mounted on the piston, a chair frame mounted on the piston to inclose the horizontal cylinder and comprising sides provided with guides in their opposed faces, a seat back slidably supported in said guides, a piston slidable in said horizontal cylinder, means connecting

the horizontal piston to the seat back, said vertical piston and the wall of the horizontal piston being formed with a passage for water under pressure, a pipe extending through the base and centrally up into said vertical piston, and a valve connected to said pipe to control the flow of water therein.

7. In a chair, the combination of an adjustable back, a seat frame, a seat formed of two sections, a pair of links on each side of the seat pivoted to said seat frame and to one of the sections so as to permit said section to be swung up and against said back wherever it may be positioned, said links supporting said section in its elevated position.

8. In a chair, the combination of a base and a chair mounted thereon to swing on a vertical axis and having two side frames provided with guides in their opposite faces, a seat frame slidable in said guides and having upwardly extending brackets at its forward corners provided with horizontal pins, a pair of bars having longitudinal slots to receive the pins, a foot-rest connecting the lower ends of said bars, and arm rests connecting to the upper ends of said bars and to the back ends of the side frames.

9. In a chair, the combination of an adjustable back, and a seat formed of two sections, one of which is adapted to be swung against said back.

10. In an adjustable chair, a back therefor adapted to move to reclining position, a seat adapted to move on its support, simultaneously with the back, power operated means for shifting the back to normal position, and means for controlling the power.

GEORGE F. CONNER.
JOSEPH WILBUR DOVE.
